UNITED STATES PATENT OFFICE

2,395,054

SCOURING AND CLEANSING DEVICE

Maurice Levine, New York, N. Y., assignor to
 James H. Rhodes & Company, Chicago, Ill., a
 corporation of Illinois

Application October 29, 1942, Serial No. 463,766

6 Claims. (Cl. 51—185)

This invention relates to cleansing devices. More particularly my invention relates to a novel and improved scouring and cleaning device of the type used for cleansing kitchen utensils and similar articles.

Cleansing devices for kitchen utensils and similar articles, as heretofore manufactured, had certain inherent disadvantages which often discouraged their use by housewives and others. One such disadvantage was due to the fact that these devices were made of metallic materials on the nature of steel wool, and when used with water they tended to rust. It was therefore often necessary to throw the entire device or pad away after only a single use. Another serious disadvantage was that the user invariably found splinters of steel had entered his or her fingers and hands after use. This further discouraged the use of such devices by housewives. It was also found that these prior devices of metallic materials retained odors which were picked up from the utensil which was being cleaned.

It is therefore one of the principal objects of my invention to provide an improved scouring and cleansing device which shall be so constructed and arranged that the above mentioned disadvantages shall be overcome, and which shall also possess certain additional advantages which will become apparent from the description to follow.

Another object of my invention is to provide a scouring and cleansing device of the class described which shall be characterized by the simplicity of its design and of its manufacture so that it will represent a general improvement in the art.

In the accompanying drawing.

Fig. 1 is a top plan view of a scouring and cleansing device constructed and arranged in accordance with my invention; and

Fig. 2 is a cross-sectional view taken substantially on the line 2—2 of Fig. 1.

Referring now in detail to the drawing I have shown a scouring and cleansing device in the form of a circular pad 10. It is understood, of course, that the pad may be made of any other desired shape. The said pad 10 comprises a plurality of convoluted or matted non-metallic strands or fibres 11 which are of such nature that they will be flexible and yet relatively hard and which at the same time will not break or splinter off, as occurs with metallic fibres. I have found that good results are obtained when I employ sisal, hemp or the like class of materials.

In order to retain the matted fibres 11 of the pad 10 in its pad-like shape and for additional

efficient cleansing purposes I prefer to impregnate the pad with a mixture of soap suitable to the purposes intended and a resinous material to lend a degree of hardness and solidity to the pad. I have found that the proportion of five pounds of soap to one pound of resin gives a satisfactory result.

If desired, and to render the device more efficient, I add to the mixture of soap and resin, a quantity of any suitable standard type of scouring powder, the quantity of scouring powder being considerably less than the amount of resin.

Other substances which I have found to produce satisfactory results when added to the mixture of soap and resin are, bentonite and/or pumice stone, each in relatively small quantities. The bentonite and/or pumice stone may be employed in addition to the scouring powder, or they may be substituted for the said scouring powder.

If desired, a necessary quantity of vegetable coloring matter may be added to the above described mixtures, to color the pad, to thereby enhance its sales value.

To make the pad more durable and to insure against unraveling and flattening of the edge portions, I provide stitching 15 looped over the periphery of the pad 10. Any suitable type of stitching may be employed, such as, for example, an overcast stitch sewn with thread.

In accordance with the provisions of the patent statutes, I have herein described the principle and purpose of my invention, together with the construction which I now consider to represent the best embodiment thereof, but I desire to have it understood that the apparatus shown is only illustrative and that the invention can be carried out by other means. Also, while it is designed to use the various features and elements in the combination and relation described, some of these may be altered and others omitted without interfering with the more general results outlined, and the invention extends to such use.

Having described my invention, what I claim and desire to secure by Letters Patent is:

1. As an article of manufacture, a scouring and cleansing device of the class described comprising matted hemp fibres formed into a pad-like unit, said pad being impregnated with a mixture containing soap, a resinous material, bentonite and coloring matter.
2. As an article of manufacture, a scouring and cleansing device of the class described comprising non-metallic matted fibres formed into a pad-like unit, said pad being impregnated with a mixture

containing soap, a resinous material and bentonite.

3. As an article of manufacture, a scouring and cleansing device of the class described comprising non-metallic matted fibres formed into a pad-like unit, said pad being impregnated with a mixture containing soap, a resinous material and scouring powder, the peripheral edge of said pad being reinforced to prevent raveling and spreading of said fibres.

4. An article of manufacture according to claim 3 in which the means employed for preventing raveling and spreading of the fibres comprises stitching.

5. As an article of manufacture, a scouring and

cleansing device of the class described comprising matted sisal fibres formed into a pad-like unit, said pad being impregnated with a mixture containing soap, a resinous material and bentonite.

6. As an article of manufacture, a scouring and cleansing device of the class described comprising non-metallic matted fibres of the nature of sisal formed into a pad-like unit, said pad being impregnated with a mixture containing soap, resin, scouring powder and vegetable coloring matter, the peripheral edge portions of said pad being reinforced with overcast stitches of thread to prevent raveling and spreading of the fibres.

MAURICE LEVINE.
